SHOCKCORD FURLING GEAR

Fred C. Werber, 807 The Crescent, and Robert Graves,
Rock Ridge, both of Mamaroneck, N.Y. 10543

Filed Dec. 20, 1967, Ser. No. 9,868

Term of patent 7 years

(Cl. D71—1)

FIGURE 1 is a top perspective view of a shockcord furling gear embodying our new design,

FIG. 2 is a top plan view thereof,

FIG. 3 is a sectional view thereof taken on line 3—3 of FIG. 2.

The herringbone-like shading on the two longitudinal strands in FIGS. 1 and 2 is understood to be indicative of the appearance of those strands over their entire length.

We claim:

The ornamental design for a shockcord furling gear, substantially as shown.
